UNITED STATES PATENT OFFICE.

JESSE DITSON, OF LITTLETON, COLORADO, ASSIGNOR TO INGERSOLL-RAND COMPANY, OF JERSEY CITY, NEW JERSEY, A CORPORATION OF NEW JERSEY.

SHANK AND BIT PUNCH.

Application filed July 3, 1925. Serial No. 41,271.

This invention relates to shank and bit punches for drill steels, but more particularly to that type of machine in which the punch pin for the drill steel is hammered 5 both into and out of the drill steel.

The objects of my invention are to provide a shank and bit punch which can be suspended within a drill sharpening shed by a chain or other flexible means and in 10 which the pin carrying member, preferably in the form of an anvil block, is adapted to be driven in one direction or the other by blows of impact delivered directly to the anvil block by the fluid actuated reciprocating hammer piston of the machine. A further object of my invention is to provide means whereby the operator can both 15 guide the punch and control the reciprocation of the hammer piston with one hand thereby allowing him the use of the other hand for actuating the drill steel clamping apparatus, or for applying additional pressure on the punch either to force the punch pin into the drill steel bore or to pull it 20 out therefrom.

Further objects of the invention will hereinafter appear and to these ends the invention consists of the combinations of elements and arrangement of parts for carrying out said objects as illustrated in the 25 accompanying drawings, in which

Figure 1 is a longitudinal sectional elevation of one form of the machine,

Figure 2 is a detail sectional elevation of 30 the valve mechanism showing the valve in a different position,

Figure 3 is a transverse sectional view taken on the line 3—3 of Figure 1 looking in the direction of the arrows.

Referring to the drawings, the machine 35 comprises the cylinder A having the front head B and the back head C connected by the usual through bolts D, not seen in Figures 1 and 2 but illustrated in Figure 3. The cylinder is provided with a valve chest E shown containing two valve chambers F and G, one chamber for the throttle valve H and the other chamber for the automatic pressure fluid distributing valve J for the 40 hammer cylinder A.

Any suitable means may be provided for 45 clamping and holding the drill steel K as by means of the clamping jaws L and O which may be the jaws on a drill sharpening machine. In the form of the machine as

shown, the shank and bit punch is adapted to be suspended as by means of a chain P in front of the drill steel K and by grasping the handle Q the machine is guided and pushed towards and pulled away from the 60 drill steel in order to permit the punch pin R to be driven into and out of the drill steel.

The machine is provided with two relatively movable impact members mounted in 65 the hammer cylinder A, one of these members comprising the hammer piston S and the other constituting the anvil block T in which the pin R is carried and held as by means of the key U. The anvil block T 70 is formed with the rearwardly extending shank V passing through the piston S and is also provided with the front striking portion or abutment W shown as a collar or shoulder and the rear striking portion in 75 the form of a nut X removably secured to the reduced screw threaded end Y of the anvil shank as by means of the cap nut Z. A washer or suitable packing a is provided between the striking portion or nut X and 80 the securing cap nut Z.

The anvil or anvil block T as it may be termed, is guided in the front head B of the machine and the cap nut Z slidable in the back head C forms a guide for the rearward portion of the anvil. The front head B is formed with an enlarged recess b to receive the collar or striking portion W of the anvil and the back head C is likewise 85 formed with the enlarged recess c to receive 90 the striking portion or nut X of the anvil.

When the machine is pushed towards the drill steel K, the striking portion or nut X of the anvil is carried into the recess c in the back head out of the path of the reciprocating hammer piston S while the forward striking portion W of the anvil is brought into the path of the piston and the blows of impact of the piston are delivered directly to the anvil to hammer the pin into 95 the steel. By pulling back on the machine the positions of the striking portions W and X of the anvil are reversed and the forward abutment W is moved out of the path of the piston while the rearward striking portion 100 or nut X is moved into the path of the piston as indicated in Figure 2 so that the blows of impact of the piston are delivered rearwardly against the striking portion X of the anvil and the pin is driven out of 105 110

the steel by blows delivered directly to the anvil.

- Pressure fluid is supplied to the machine through the inlet *d* controlled by the throttle valve *H* having the valve stem *e* pivotally connected at *f* to the depending portion *g* of the handle *Q* which handle is in turn pivoted at *h* to the back head *C*. A guide pin *j* on the back head *C* enters a guide slot *k* in the handle *Q* so that the handle may be rocked about the pivot *h* to control the throttle valve *H* and permit pressure fluid to be supplied to the machine or shut off from the machine as desired.
- After the machine has been pushed forward by hand to center the pin in the drill steel, the handle *Q* is rocked to open the supply of pressure fluid to the hammer cylinder. The distributing valve *J* may be of any suitable form but in this instance is provided with the heads *o*, *p*, *q* and *r* controlling suitable ports and passages in the valve chest for supplying pressure fluid alternately to the ends of the hammer cylinder and exhausting pressure fluid therefrom as indicated by the arrows. The valve chest in this instance is provided with exhaust ports *s* and *t* and also with the kicker ports *u* and *v* for operating the valve as is understood by those skilled in the art.

After the pin *R* has been driven into the drill steel, the machine is pulled rearwardly which removes the striking portion *W* of the anvil from the path of the piston and carries the striking portion *X* into the path of the piston and by leaving the throttle valve *H* open, the hammer *S* drives the pin out of the drill steel.

I claim:

1. In a shank and bit punch for drill steels, the combination of means for holding the drill steel, a hammer cylinder adapted to be flexibly suspended within working distance of the said means for holding the drill steel, a fluid actuated reciprocating hammer piston in said cylinder, an anvil block mounted in said cylinder and

having a shank extending through the piston, a pin carried by said anvil block and adapted to enter the drill steel, an abutment 50 on the anvil block forwardly of the hammer piston to receive the blows of the piston for driving the anvil block and pin in one direction, another rearward abutment on the anvil block to receive the blows of the piston for driving the anvil block and pin in the opposite direction, a throttle valve normally held closed by spring means for actuating the said hammer piston, and a hand grip located on the said cylinder for guiding 60 the punch with relation to the drill steel and adapted to control the said throttle valve for actuating the hammer piston.

2. In a shank and bit punch for drill steels the combination of means for clamping the drill steel, a hammer cylinder adapted to be flexibly suspended in the same longitudinal plane as the said drill steel clamping means and within a suitable working distance therefrom, a fluid actuated reciprocating hammer piston in said cylinder, an anvil block mounted in said cylinder and having a shank extending through the piston, a pin carried by said anvil block and adapted to enter the drill 75 steel, an abutment on the anvil block forwardly of the hammer piston to receive the blows of the piston for driving the anvil block and pin in the opposite direction, a throttle valve for controlling the reciprocation of the piston, spring means for normally holding the throttle valve closed, a grip attached to the cylinder for manually driving the cylinder towards the drill steel or for withdrawing it from the drill steel, and means connecting the said handle with the throttle valve whereby manual force applied either to drive the cylinder towards the drill steel or to withdraw it from the drill steel will open the throttle valve and cause reciprocation of the piston.

In testimony whereof I have signed this specification.

JESSE DITSON.
